UNITED STATES PATENT OFFICE.

FRANK J. WINGLER, OF DETROIT, MICHIGAN.

GAS MOTOR.

Application filed October 26, 1925. Serial No. 64,831.

My invention relates to a new and useful improvement in a gas motor and has for its object the provision of a gas motor, so constructed and arranged as to permit the use of a minimum number of cylinders with a maximum number of impulses delivered to the drive shaft.

Another object of the invention is the provision of a gas motor having a drive shaft 10 provided with an enlarged gear, adapted for being driven with a piston operated shaft, for effecting a rotation of the drive shaft of the motor.

Another object of the invention is the provision of a gas motor having a plurality of stationary cylinders, each adapted for rotating a shaft upon which is mounted a gear for effecting a rotation of a meshing gear, which is fixedly mounted upon the drive shaft of the engine.

Another object of the invention is the provision of a gas motor which may be well balanced and substantially free from vibration.

Another object of the invention is the provision of a gas motor which will be compact, durable and consisting of a minimum number of parts, all accessible, and easy to regulate and repair.

Another object of the invention is the provision of a gas motor which will use a minimum amount of oil and gas.

Other objects will appear hereinafter.

The invention consists in the combination and arrangement of parts hereinafter described and claimed.

The invention will be best understood from a reference to the accompanying drawings, which form a part of this specification 40 and in which,

Fig. 1 is a side elevational view of the invention, taken on substantially line 1—1 of Fig. 5.

Fig. 2 is a side elevational view, illustrating the cylinders used in the invention.

Fig. 3 is a fragmentary sectional view, taken on substantially line 3—3 of Fig. 2,

Fig. 4 is a fragmentary sectional view, taken on substantially line 4—4 of Fig. 2,

Fig. 5 is a sectional view, taken on substantially line 5—5 of Fig. 1,

Fig. 6 is a view taken on substantially line 6—6 of Fig. 2.

As shown in the drawings, a pair of cylinders 9 and 10 are illustrated, although, from the description, it will appear evident

that any number of cylinders may be used, the preferable number being shown. Each of these cylinders is constructed similarly and a detailed description of one will suffice for both. As shown in Fig. 5, there is fixedly mounted upon the drive shaft 11 of the engine a fly wheel 12, having an enlarged rim 13 to provide the necessary weight for the proper momentum. This drive shaft is journaled in bearings 14 and 15, which are mounted in a housing 16, the forward wall thereof being offset, to provide the recess 17. Fixedly mounted, by means of screws 18, or in any other desired manner, is a wheel 19 having teeth 20 formed on its periphery. The teeth 20 are adapted for meshing with a gear 21 mounted on the shaft 22, which is journaled in bearings 23 mounted in the housing 16. As clearly appears in the drawings, this shaft 22 is provided with a plurality of cams 24, each adapted for actuating a tappet positioned in the cylinders 9 and 10. As shown, each of these cylinders 9 and 10 is provided with a pair of tappet actuating rods 35 and 36, the tappet 35 serving to actuate the intake valve and the rod 36 serving to actuate the exhaust valve. Each of the cylinders is provided with a passage 27, which serves to conduct water around the cylinder for cooling purposes this structure being well known. At the upper end of each of the cylinders, an opening 27' is provided in which is pressed a sleeve 28 having an opening 29 formed therein, adapted to register with an opening formed in the cylinder, which is in communication with the source of fuel supply. Positioned in the opening 27 is a plate 30, which is secured in operative position in close engagement with a gasket 31 on the sleeve 28, by means of a nut 32.

Projecting upwardly from the cylinder 9, at the opening 27, is a sleeve 33, which is angularly turned at its upper end, as shown in Fig. 3 to provide a space for the reception of the cup-shaped member 34. Threaded into the cup-shaped member 34 is an actuating rod 35 having a hexagonal head 36 engaging with the cam 24. The cup 34 is adapted to engage the valve stem 37, which projects upwardly from the valve 38. A suitable spring 39 is mounted on the valve stem for the purpose of retaining it normally in closed position. The structure 100 of the exhaust valve is similar to the intake valve and for the purpose of description,

only one is set forth in detail. Slidably mounted in the cylinder 9 is a piston 40 connected by the piston rod 41 to a crank 42 on the shaft 43. The shaft 43 carries 5 the bevel gear 44, which meshes with the teeth 20. As shown in the drawings, suitable brackets 45 serve to support the cylinders on the housing 16. As shown in the drawings, the relative position of the intake 10 ports and the exhaust ports on the pair of cylinders is offset, the cams being staggered, so as to effect the proper operation of the cylinders. The structure is such that the 15 valves, which are regularly acting valves, open and close in one cycle, one piston moving on its power stroke, while the other is moving on its intake stroke.

In operation, a suitable ignition system 20 will be used, but inasmuch as this ignition system forms no part of the present invention and may be of a type which is well known, a detailed description of the same is not supplied.

When the device is attached to a drive 25 shaft 11 in the manner indicated, a cranking of the engine will cause the wheel 19 to rotate, thus effecting a rotation of the gears 21 and 44. This rotation of the gears 21 and 44 will effect the desired operation of the 30 intake and exhaust valves of the engine and the timing device will supply the necessary ignition. It is believed evident, from the description given, that each cylinder may 35 deliver a number of explosions for each revolution of the drive shaft 11. The number of explosions delivered by each cylinder during each revolution of the drive shaft 11 will be determined by the size of the gears 44 and the size of the wheel 19, the ratio existing 40 between the number of teeth on the gears 44 and 21 and the teeth 20 being a factor determining the rapidity of operation of the cylinders.

It is believed evident that a large range of 45 adjusting is possible with a motor of this class and that, on account of the maximum number of explosions for a single rotation of the drive shaft, more power will be delivered than with the ordinary engine. An 50 increase in force is also obtained by the use of this engine, inasmuch as the rotating thrust is delivered to the drive shaft of the engine on a long radius, the distance from the drive shaft of the engine to the periphery of the wheel 19 determining this radius 55 and affecting the leverage of the engine. On account of the rapidity with which the explosions may take place in a minimum

number of cylinders, the vibration will be considerably reduced over the engines now in use.

While I have illustrated and described the preferred form of structure, I do not wish to limit myself to the precise form of structure shown, but desire to avail myself of such variations and modifications as come within the scope of the appended claims.

Having thus described my invention, what I claim as true and desire to secure by Letters Patent is:

1. A motor of the class described, comprising a drive shaft; a gear wheel mounted on said drive shaft and rotatable therewith; a plurality of internal combustion cylinders; a plurality of gears meshing with said gear wheel and rotatable upon operation of said internal combustion cylinders; and an additional gear meshing with said first mentioned gear wheel for controlling the periods of operation of said internal combustion cylinders.

2. A motor of the class described, comprising a drive shaft; a fly wheel mounted thereon; a ring gear mounted on the fly wheel at or near its periphery; a plurality of internal combustion cylinders; a crank shaft for each of said cylinders, operable thereby; a gear mounted fixedly on each of said crank shafts and meshing with said first mentioned gear for effecting a rotation of said drive shaft upon the rotation of said crank shafts; an intake valve for controlling the flow of fluid to each of said cylinders; an exhaust valve for controlling the exhaust from each of said cylinders; a cam shaft for operating said valves; and a gear fixedly mounted on said cam shaft meshing with said first mentioned gear and rotatable upon the rotation of said drive shaft.

3. A motor of the class described comprising a drive shaft; a gear wheel mounted on said drive shaft and rotatable therewith; a plurality of internal combustion cylinders; a plurality of gears meshing with said gear wheel and rotatable upon operation of said internal combustion cylinder; control valves for each of said cylinders for controlling the intake and exhaust thereof; an additional gear meshing with said first mentioned gear; and means operable upon the rotation of said additional gear for operating at periodic times, said exhaust and control valves.

In testimony whereof, I have signed the foregoing.

FRANK J. WINGLER.
